UNITED STATES PATENT OFFICE.

CHARLES W. STEVENS, OF EAST ORANGE, NEW JERSEY.

APPARATUS FOR SHAPING HAT-CROWNS.

No. 843,640.

Specification of Letters Patent.

Patented Feb. 12, 1907.

Application filed April 14, 1906. Serial No. 311,694.

To all whom it may concern:

Be it known that I, CHARLES W. STEVENS, a citizen of the United States, residing at East Orange, Essex county, State of New Jersey, have invented certain new and useful Improvements in Apparatus for Shaping Hat-Crowns, of which the following is a full, clear, and exact description.

My invention relates to apparatus for producing a telescopic shape or effect in soft felt hats.

The object of the invention is to provide a simple form of apparatus which may be employed to give a telescopic shape to the crowns of soft felt hats and the like.

The invention consists in improvements the principles of which are illustrated in the accompanying single sheet of drawings.

Briefly, it comprises two rings carrying stops on their exteriors. One ring is adapted to fit inside the crown of the hat and the other to fit in the telescopic portion outside the crown. Both rings are adjustable in size, and the stops are adjustable in position, so that varying proportions in the shapes may be produced.

Figure 1 is a vertical sectional view of the apparatus of my invention, showing a hat in place and with its crown telescoped. Fig. 2 is a plan view of the inner crown-ring. Fig. 3 is a plan view of the outer crown-ring. Fig. 4 is a detailed perspective view of one of the stop members.

1 is the inner ring or tubular member, adapted to fit within the crown of the hat 2.

3 is the outer ring, adapted to force the material of the crown of the hat inside the edge of the ring 1 to form the telescopic effect.

4 is a stop carried by the ring 1. Four of these stops are preferably provided.

5 is a stop carried by the ring 3. Three of these are preferably provided.

The hat is placed over the upper edge of the ring 1 and drawn down until the brim or base of the crown strikes the stop 4. The top of the crown is then depressed and the ring 3 placed inside the depressed portion, the stop 5 resting against the edge 6 of the crown. The whole apparatus is then turned over and the center of the crown pressed out, as shown in Fig. 1, the lower edge of the ring 3 serving to produce the base 7 of the curve in the crown. Different sizes of rings may of course be provided for different-sized hats and the stops 4 and 5 placed at different distances from the upper and lower edges of

their respective rings, so as to produce the portions of telescope desired. I prefer, however, to make both rings adjustable in size for different-sized hats and to make the stops 4 and 5 vertically adjustable for producing different telescopic effects.

8 indicates a screw-post carried by the ring 1 and projecting through a slot 9 in the vertical portion of the lug 4.

10 is a thumb-nut for clamping the lug in place. Each of the lugs on the ring is mounted in the same way, so that all or any may be adjusted to produce the desired height or shape of the crown. Of course if two of the lugs are placed lower than the other two the crown of the hat will be higher on one side than the other.

11 is a screw-post secured to ring 3 and projecting through the slot 12 in the vertical portion of the lug 5. 13 is a clamp-nut therefore, so that the lug 5 may be vertically adjusted. Each of the lugs on the ring 3 are mounted in the same way, so that the depth from rim 6 to groove 7 may be produced as desired. By adjusting one of the lugs 5 at a different distance from the lower edge of the ring 3 than the others a one-sided or tilted effect of the crown may be produced. The rings are preferably formed of strips of sheet metal, with their ends overlapped.

14 is a screw-threaded post carried by the outer flap of the ring 1 and projecting into the interior through the slot 15 in the other flap. 16 is a clamp-nut. These clamps are provided near the top and bottom of the ring 1, so that the ring may be adjusted to suit any sized hat. The upper ring 3 is similarly formed and has a screw-post 17, carried by the outer flap, projecting through the slot 18 and carrying a clamp-nut 19.

By means of this apparatus telescopic crowns may be formed in soft felt hats with rapidity and of uniform shape, as desired.

What I claim is—

1. Apparatus for producing telescopic effects in soft felt hats and the like comprising two rings adjustable in size, one larger than the other, and outwardly-projecting vertically-adjustable stops carried by each ring for the purpose specified.

2. Apparatus for producing telescopic effects in soft hats and the like comprising two rings, adjustable in size, and outwardly-projecting stops carried by each ring.

3. Apparatus for producing telescopic crown effects in soft hats comprising two

rings one larger than the other, and vertically-adjustable stops carried by each ring for the purpose specified.

4. Apparatus for producing telescopic crown effects in soft hats comprising an inner ring, four adjustable stops outwardly projecting therefrom, an outer ring of smaller diameter, and three outwardly-projecting stops carried thereby.
- 10 5. Apparatus for producing telescopic crown effects in soft hats comprising a sheet-

metal ring formed with overlapping flaps, screw-posts carried by one of said flaps and projecting through slots in the other flap, clamp-nuts for said posts, and outwardly-projecting independent vertically-adjustable lugs carried by said ring for the purpose specified. 15
